JOSEPH KOENIG, OF MANITOWOC, WISCONSIN; REMUS KOENIG AND RUBY K. ELLIS
ADMINISTRATORS OF SAID JOSEPH KOENIG, DECEASED

HOT-AIR ENGINE

Application filed May 13, 1926. Serial No. 108,800.

This invention relates to hot air engines.

In hot air engines as heretofore constructed, it has been the usual practice to provide extensive heating surfaces with a consequent increase in bulkiness of the engine in order to secure the quick heating of the air. This was necessary, as it must be appreciated, that the heating of the air must occur relatively quickly in order to secure the highest efficiency for the engine and in order to insure a proper interchange of heat.

This invention is designed to overcome the defects noted above, and objects of this invention are to provide a novel form of hot air engine which is relatively compact, in which a very intimate mixing of the heated products of combustion and the air in the treating cylinders is secured so that these gases may commingle and produce a very good transfer of heat through the entire volume of air in the treating cylinders, and also to provide means whereby this interchange may be very quickly effected without requiring an excessively large treating cylinder.

Further objects are to provide a novel form of hot air engine in which the minimum amount of fuel is required for heating the air and in which a very compact and serviceable arrangement of parts is secured.

An embodiment of the invention is shown in the accompanying drawings, in which:

Figure 1 is an elevation partly in section of the hot air engine.

Figure 2 is a detail view partly broken away showing one of the quick acting cams.

Figure 3 is a further detail view showing the cam for operating the valves.

Referring to the drawings, it will be seen that the hot air engine comprises a main working cylinder 1 within which a piston 2 is mounted. The piston is operatively connected to a crank 3 of the crank shaft or drive shaft 4, such shaft being carried in any suitable bearings. This drive shaft further carries a pair of small cranks 5 and 6 which operate the pistons 7 and 8 in the air pump cylinders 9 and 10 respectively. Further, it is to be noted that a quick acting cam 11 is carried by the crank shaft and operates the

cross head 12—see Figure 2. This cross head is connected by means of links 13 with a rocking beam 14 whose opposite ends are similarly connected by means of links to the piston rods 15 and 16 of the air treating cylinders 17 and 18. These air treating cylinders are connected to opposite ends of the working cylinder 1 and further, are connected through valves 19 and 20 to the upper sides of the pump cylinders 9 and 10 for a purpose hereinafter to appear.

The treating cylinders are of similar construction and one only need, therefore, be described in detail.

Consider for example, the cylinder 17. It is provided with an internal sleeve 21 within which the piston or air shifter 22 slides. This shell or inner sleeve is carried in any suitable manner as by means of the upper flange 23 and the space above the piston 22 communicates with the space between the sleeve 21 and the outer casing by means of a plurality of apertures 24. It is to be noted that the piston 22 is provided with an overhanging sleeve 25 and that both the sleeve 25 and the head of the piston are insulated by means of the heat insulating layer 26. Further, it will be noted that the sleeve 25 stops short of the bottom of the cylinder, and consequently, a passage 27 is formed between such lower end and the end of the cylinder so that the air may pass through this annular passage into the space below the piston 22. Further, it is to be noted that the lower end of the cylinder is cooled. This may be secured in any suitable way as by means of the water jacket 28, suitable inlet and outlet apertures being provided, as indicated, to permit continuous flow of a cooling agent.

The upper end of the air conditioning cylinders are provided with domes as for example, as shown in Figure 1, the cylinder 17 is provided with a dome 29 into which the delivery pipe 30 for the compressed air passes. Further, it is to be noted that fuel under pressure may be supplied this inwardly passing stream of air by means of the valve 31, such valve being controlled in a manner hereinafter described. The dome 29 is provided with a spark plug 32 for ignit-

ing the inwardly flowing charge or combustible mixture.

It is to be noted that each of the air pumps is provided with an inwardly opening inlet valve 33 and with an outwardly opening valve 34. Further, the upper portion of each of the air pump cylinders 9 and 10 is provided with a discharge valve indicated respectively by the reference characters 35 and 36.

Means are provided for simultaneously operating the valves for controlling the admission of fuel and the admission and discharge of the pressure gases to the upper side of the pump cylinders. For example, the valves 19 and 35 may be provided with crank arms joined by a link 37, and similarly, the valves 20 and 36 may be operatively joined by the link 38. The valves 35 and 36 are also provided with slotted arms 39 and 40 which are operated by pins carried by a transverse bar 41 rigidly mounted on the reciprocatory rod 42. Further, the valves 19 and 20 are provided with arms 43 and 44 respectively which are connected by means of links 45 and 46 with the arms 50 and 51 respectively of the fuel valves.

In the operation of the apparatus, it is intended that the air pumps compress air and deliver a fraction of the volume of the air conditioning cylinders to the air conditioning cylinders. This fresh air delivered to these cylinders mixes with fuel and is ignited by the spark plug or in a suitable manner, and expands the gases contained in the air conditioning cylinders so that the most intimate mixing occurs with consequent efficient transfer of the heat, due to the combustion, to the entire mass of gases in the air conditioning cylinders.

It is to be noted further that the sleeves 21 of the air conditioning cylinders act as regenerators so that when the air is passed into the lower end of the air treating cylinders by flowing through the apertures 24 and downwardly between the shell 21 and the outer casing of the cylinders, such shell extracts a material amount of heat from the air prior to its arrival at the chilled end of the cylinders.

Consider one half cycle of operation, for example, when the working piston 2 is making a downward stroke, the air in the air conditioning cylinder 17 is expanded by the mixing of the products of combustion from the incoming charge with the air already in the cylinder. This expanding increases the pressure within the air conditioning cylinder 17 and forces the working piston downwardly. Further, it is to be noted that a part of the pressure gases in the cylinder 18 is employed for aiding in the operation of the pump piston 8. This pressure gas is passed to the cylinder 10 by way of the valve 20. When, however, the piston in the air pump

cylinder approximately completes its stroke downwardly, the exhaust valve 36 opens and discharges the pressure gases to the outside air. The other half cycle is identically like this except that the air conditioning cylinder 18 is substituted in the operation for the cylinder 17 and the pump cylinder 9 is substituted for the cylinder 10.

It will be seen further that the pumps 9 and 10 are so timed that they will force a charge of compressed air into the appropriate air treating cylinder at the time when the air treating cylinder is to deliver pressure gases to the working cylinder. Further, by having the fuel mix with the incoming fresh air, it is clear that the fuel will readily burn and will heat the air or other gases remaining in the air conditioning cylinders.

Consider for example, the rising of one of the air shifting pistons, for example, the piston 22. When this piston rises, as for instance, just prior to the rise of the working piston 2, the air and gases contained above the piston 22 are passed through the apertures 24 and flow downwardly between the sleeve 21 and the outer shell of the air conditioning cylinder 17. The sleeve 21 extracts heat from the passing hot gases or air prior to its arrival at the chilled end of the cylinder. When the air arrives at the chilled end, it is further contracted, and thus, the pressure within the air conditioning cylinder is lowered and the air contracted so as to receive the air discharged by the upward motion of the working piston 2.

It is to be understood that the air pumps are so proportioned with relation to the air conditioning cylinders that they deliver a fraction only of the total volume of the air conditioning cylinders. For example, an efficient relation may be secured by designing the air pump cylinders to deliver approximately 15% of the volume of the air conditioning cylinders for each stroke of the pumps. In other words, the apparatus is essentially a hot air engine and not an explosive internal combustible engine. The burning of the mixture in the air conditioning cylinders is for the purpose of securing the maximum interchange of heat for the gases within the air conditioning cylinders by actually mixing the heated products of combustion with the air or gas in the cylinders. In this way, the maximum efficiency and compactness is secured together with quick heat interchange.

The pump cylinders may be so designed as to put the apparatus under a higher pressure than atmospheric, as the practical design or demands may require, whereby the size of the apparatus may be reduced.

Where the chambers are large, tie rods 21' may be employed to hold the heads of the chambers together.

Although the invention has been described in considerable detail, such description is intended as illustrative rather than limiting as the invention may be variously embodied and as the scope of such invention is to be determined as claimed.

I claim:

1. A hot air engine comprising a working cylinder having a working piston therein, a crank shaft driven from said working piston, a pair of air conditioning cylinders having one of their ends directly connected to opposite ends of said working cylinder and having cooled ends opposite the ends connected to the working cylinder, each of said air conditioning cylinders having a sleeve therein extending from adjacent the cooled end of the cylinder to adjacent the other end thereof, an air shifting piston slidably mounted in each of said sleeves, a walking beam operatively connected to said pistons and driven from said crank shaft, an air pump for forcing air into the other end of each of said air conditioning cylinders, means for admitting fuel to said last mentioned end of each of said air conditioning cylinders, means for igniting said fuel, and means for discharging a portion of the gas in each of said air conditioning cylinders to the air pump corresponding to such cylinder to aid in the compression of air in said air pump.
2. A hot air engine comprising a working cylinder having a working piston therein, a crank shaft driven from said working piston, a pair of air conditioning cylinders having one of their ends directly connected to opposite ends of said working cylinder and having cooled ends opposite the ends connected to the working cylinder, each of said air conditioning cylinders having a sleeve therein extending from adjacent the cooled end of the cylinder to adjacent the other end thereof, an air shifting piston slidably mounted in each of said sleeves, a walking beam operatively connected to said pistons and driven from said crank shaft, an air pump for forcing air into the other end of each of said air conditioning cylinders, means for admitting fuel to said last mentioned end of each of said air conditioning cylinders, means for igniting said fuel, and means for discharging a portion of the gas in each of said air conditioning cylinders to the air pump corresponding to such cylinder to aid in the compression of air in said air pump.
3. A hot air engine comprising a working cylinder having a working piston therein, a crank shaft driven from said working piston, a pair of air conditioning cylinders having one of their ends directly connected to oppo-

site ends of said working cylinder, means connecting opposite ends of said air conditioning cylinders, and air shifting pistons slidably mounted in each of said cylinders, a walking beam operatively connected to said pistons and driven from said crank shaft, an air pump for forcing air into the other end of each of said air conditioning cylinders, means for admitting fuel to said last mentioned end of each of said air conditioning cylinders, means for igniting said fuel, and means for discharging a portion of the gas in each of said air conditioning cylinders to the air pump corresponding to such cylinder to aid in the compression of air in said air pump.

4. A hot air engine comprising a working cylinder having a working piston therein, a crank shaft driven from said working piston, a pair of air conditioning cylinders having one of their ends directly connected to opposite ends of said working cylinder, means connecting opposite ends of said air conditioning cylinders, and air shifting pistons slidably mounted in each of said cylinders, means carried by said crank shaft for quickly moving the shifting pistons to opposite ends of the air conditioning cylinders at the completion of each stroke of the working piston, an air pump for forcing air into the other end of each of said air conditioning cylinders, means for admitting fuel to said last mentioned end of each of said air conditioning cylinders, means for igniting said fuel, and means for discharging a portion of the gas in each of said air conditioning cylinders, means for igniting said fuel, and means for discharging a portion of the gas in each of said air conditioning cylinders to the air pump corresponding to such cylinder to aid in the compression of air in said air pump.

In testimony that I claim the foregoing I have hereunto set my hand at Milwaukee, in the county of Milwaukee and State of Wisconsin.

JOSEPH KOENIG.
